UNITED STATES PATENT OFFICE.

LIONEL M. WOLFFSOHN, (NOW BY JUDICIAL CHANGE OF NAME LIONEL M. WOOLSON,) OF WEEHAWKEN, NEW JERSEY, ASSIGNOR, BY MESNE ASSIGNMENTS, TO BIJUR MOTOR APPLIANCE COMPANY, A CORPORATION OF DELAWARE.

ELECTRICAL APPARATUS FOR AUTOMOBILES.

1,330,567.

Specification of Letters Patent. Patented Feb. 10, 1920.

Application filed February 10, 1917. Serial No. 147,889.

To all whom it may concern:

Be it known that I, LIONEL M. WOLFFSOHN, a citizen of the United States, and a resident of Weehawken, in Hudson county, 5 State of New Jersey, have invented an Improvement in Electrical Apparatus for Automobiles, of which the following is a specification.

This invention relates to electrical apparatus and with regard to certain more specific features, to the construction and to the mounting of a dynamo electric machine and related power-transmitting parts.

One of the objects thereof is to provide apparatus of the above type of enhanced simplicity and effectiveness. Another object is to provide a simple, secure and inexpensive mounting for an electric starting motor with relation to an internal combustion engine. Another object is to provide a mounting of the above type in which the apparatus is readily assembled or dismounted and is nevertheless rigidly held assembled in condition for efficient action. Another 25 object is to provide simple and effective means for distributing the lubricating substance and confining it to parts of the apparatus where it is useful.

Other objects will be in part obvious and 30 in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings in which are shown one or more possible embodiments 40 of this invention, Figure 1 is a side view partly in section showing the mounting of the apparatus on an automobile engine, the invisible parts of the shaft being shown dotted.

Fig. 2 is a view similar to Fig. 1 with parts broken away to reveal the interior construction, showing the same apparatus mounted on a modified form of engine leg.

Fig. 3 is a transverse section taken on the 50 line 3—3 of Figs. 1 and 2.

Fig. 4 is a fragmentary view of a modified form of my invention.

Similar reference characters refer to similar parts throughout the different views of the drawings.

Referring now to Figs. 1 and 2 of the drawings, there is shown a motor unit 1, the exterior of which consists of a motor casing 2 having a head 3 at the left end, and at its right, a cup shaped end head 4, also acting 60 as a housing for the inclosed drive 13. The intermediate portion of the casing apart from the heads, I designate as the yoke. The cup-shaped end head has an outstanding flange 5 between its ends, with perforated 65 lugs 25, and the part of the head beyond said flange projects through an opening 24 in the engine leg 6, the latter term designating that part of the engine casing which incloses the flywheel. A smaller flange portion 12 contiguous to flange 5 completely fills the opening 24 in the motor leg 6, thus further helping to steady the device. The entire unit is secured to the engine leg by bolts 7 passing therethrough and through 70 the perforated lugs 25. Reinforcing ribs 8, integral with the motor head, extend between the flange 5 and enlarged skirt portion 26, which surrounds or telescopes over the end of the motor casing 2. Relatively 80 small screws 29 are passed through said skirt portion 26 and are threaded longitudinally of casing 2, to draw the motor into proper alignment with the head, when bolts 9 extending preferably radially of the casing, 85 can be placed in position to firmly secure the motor to head 4.

Referring further to Figs. 1 and 2, there is shown a shaft 10 having two bearings, one within end head 3 and the other, as shown at 90 11, in the end of combined motor head and drive housing 4, the shaft being unsupported between said bearings. The end-heads of a dynamo it will be understood are those elements thereof that lodge, support or carry 95 the armature or rotor bearings. On that part of the shaft 10 extending beyond the armature of the motor, there is mounted an automatic engine starting drive, 13 of the outboard type consisting broadly of pinion 100

14 coöperating with flywheel gear 15, said pinion being actuated by a combined shifting and torque transmitting means 16, broadly of barrel form, and in threaded relation to the shaft 10.

5 The unit 16-14 is maintained between springs 17 and 18 and spring 17 is maintained in position by flanged sleeve 21 secured to shaft 10. The interior construction of this form of driving connection, other than the shaft, is not shown and further detailed description thereof is not necessary, as this form of drive by itself is the subject-matter of copending application of

15 Joseph Bijur Serial No. 145,839, filed Feb. 1, 1917. It may be here noted that upon starting the motor, the unit 16-14, is automatically urged into coöperation with gear 15, under all conditions of operation, and 20 after the engine has started, this unit automatically returns to idle position. Though other forms of driving connection may be used with good results it is to be understood that there are particular advantages when 25 this specific form of engine starting drive is employed. It is seen that the end head 4 performs the additional function of inclosing, or constituting a housing for the engine starting drive.

30 The shaft 10 as shown in Fig. 1 is formed preferably of greatest diameter near its center since the greatest amount of stiffness is needed in that region, and it is reduced in diameter toward its bearings. It is to be noted, also, that the various reductions in 35 the part of the shaft projecting beyond the armature, may be the same as in my copending application above referred to, as clearly shown in Fig. 1.

40 By my construction, I thoroughly lubricate the power-transmitting parts from the engine casing. To effect convenient lubrication of the relatively inaccessible bearing 11, an oil duct 27 is employed leading from 45 the outside of the engine leg, where is located a common form of closure 33 to bearing 11, and being held against the outside of housing or head 4, by strap 34. I, also, provide means between the armature and 50 the drive to prevent the entry of lubricating oil from the latter to the interior of the motor. For this purpose, I have devised a special form of oil-thrower consisting of a plate 19 clamped against the shoulder 20 55 formed substantially in the plane of the end of casing 2 being located between the portion of shaft 10 bearing the armature and the somewhat reduced portion on which the drive is mounted and having a peripheral 60 deflection, or flange 27, on the side away from the motor. The plate 19 is secured for rotation with the shaft 10 by flanged sleeve 21, between which and the shoulder 20, it is securely held. Since both shoulder 65 20 and flanged sleeve 21 rotate with

shaft 10 the plate 19 is constrained to rotate with it also. Obviously other means could be employed for securing the plate 19 but there are particular advantages in the use of the peculiar securing means employed. 70

An annular element 22 of any desired material is preferably clamped between the end of casing 2 and the combined end head and drive housing 4 and has its inner periphery within the outer periphery of the 75 flange of plate 19, and is located substantially in the plane of this plate. Other forms of oil-throwers might be employed effectively but it is to be understood that there are particular advantages in the specific construction described. 80

If an end head were disposed between the armature and the drive to act as an intermediate bearing for the shaft and tending to prevent the entry of oil into the casing 2, not only would the construction involve a greater expense for material, but, since in the outboard type of drive as is well known, the outer bearing 11 cannot be dispensed with, the difficulty of forming 90 three bearings in proper alinement, obviously much greater than that of alining two bearings would be encountered.

The flywheel 28 having a geared portion 15 is shown extending through an opening 95 23 in the combined end head and drive housing 4, and as shown, the geared portion 15 is on the side remote from the motor. If the gear 15 were located on the side of the flywheel nearer the motor, the flange 5 would have to be located at a point on head 4 further removed from the motor by a distance substantially equal to the width of the flywheel, and thus the casing 2 and its inclosed heavy motor parts would be located at a 100 correspondingly greater distance from the engine leg 6 when the device is assembled. This would produce such a preponderating moment on the securing bolts 7 attaching flange 5 to the engine leg 6, due to the greater 105 weight of the parts on the outside of the leg and to the relatively greater distance of both the center of gravity and of inertia of such parts from this leg, that auxiliary 110 supporting or holding means would be rendered necessary to maintain the construction in operative assembly particularly under the great strain of starting the engine. By my construction the strains are so well balanced 115 on opposite sides of the flange, that the flange support by itself is sufficient to effectively support the construction under all conditions of operation without the aid of any auxiliary support or holding means.

Where, as shown at 30 in Fig. 2, the engine leg is very close to the flywheel, as is the case in some engines, the leg is preferably formed with deflection 31, as shown, so that the surface 32, to which the motor is secured may be sufficiently spaced from the 120 125 130

flywheel gear, to make room for the automatic drive without necessitating any other modification of the construction shown in Fig. 1 and without sacrifice of efficiency or reliability.

In Fig. 4, I have shown an arrangement which may be particularly advantageous for long or relatively heavy motors. The flange 5¹ is shown near the center of inertia of the 10 motor, in other words, with heavy or long motors, nearer the armature, than is flange 5 in the other views. A deflection 31¹ is formed on the engine leg 30¹, so that surface 32¹ to which flange 5¹ is secured is suitably 15 located to place the drive and the flywheel gear in proper relative position.

In the operation of the device, any oil which may find its way from the engine starting drive 13 or its supporting shaft, 20 toward the armature, will be arrested by the plate 19 and because of its rapid rotation with the motor, the oil will be thrown by centrifugal force to the outer part of the casing. It will then either return to the 25 shaft to be again thrown out by the plate 19, or it will find its way to the lower part of member 4, and will be denied access to casing 2 and the armature by annular member 22.

30 It will thus be seen that there is herein described apparatus in which the several features of this invention are embodied, and which apparatus in its action attains the various objects of the invention and is well 35 suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not 45 in a limiting sense.

Having described my invention, what I claim as new and desire to secure by Letters Patent is:

1. In a starting motor unit, in combination, a rotor having a shaft, a casing for said rotor carrying bearings for said shaft, and a driving member for an engine connected to be driven from said shaft and mounted between said rotor and the bearing 55 nearest thereto on one side thereof.

2. In a starting motor unit, in combination, a rotor having a shaft, a yoke encircling said rotor, a pair of end heads mounted upon said yoke, each provided with a 60 bearing for said shaft, and an outboard shiftable driving connection mounted upon said shaft and disposed between said rotor and the proximate bearing on one side thereof.

65 3. In apparatus of the class described, in

combination, a starting motor, having a shaft, a yoke and a head, said shaft projecting beyond said yoke at the end remote from the head, an automatic engine starting drive, threaded on the projecting end 70 of said shaft, and a housing for said drive, having a part secured with respect to said yoke, and having a bearing for the extended end of said shaft, said shaft being unsupported between said two bearings. 75

4. In apparatus of the class described, in combination, a starting motor having a casing, bearings in said casing, an engine starting drive within said casing between said bearings, and means for wholly supporting 80 said motor on a non-rotating part associated with said engine, at a point between said bearings.

5. In apparatus of the class described, in combination, an engine leg, a starting motor, 85 heads for said motor, having bearings, an engine starting drive between said bearings and extending within one of said heads, and a flange on said motor, near the center of inertia thereof, secured around an opening in said leg, said motor being unsupported at its ends. 90

6. In apparatus of the class described, in combination, an engine leg, a starting motor having a shaft, heads for said motor, 95 one of said heads being cup-shaped, bearings for said shaft near the outer ends of said heads, an automatic engine starting drive threaded on said shaft and extending through said cup-shaped head and a flange 100 rigid with respect to said cup-shaped head, at a point spaced from its outer end and near the center of inertia of said motor, and secured to said engine leg, said motor being unsupported at its ends. 105

7. In apparatus of the class described, in combination, an engine leg, a starting motor, having a shaft, and a yoke for said motor provided with heads, one of said heads being cup-shaped, bearings for said shaft, 110 near the extreme ends of said heads, an automatic engine-starting drive on said shaft, extending through said cup-shaped head, said head being telescoped over said yoke, and having an outstanding flange near the 115 center of inertia of the motor, secured to said engine leg, and stiffening webs connecting said flange and said telescoped portion.

8. In apparatus of the class described, in 120 combination, a motor, heads for said motor, one of said heads being cup-shaped, a driving connection for an engine, disposed in said cup-shaped head, and means for supporting said motor on a non-rotating part 125 associated with said engine, at a plane near the center of inertia of said motor.

9. In apparatus of the class described, as an article of manufacture, a combined motor head and housing for an engine drive, 130

comprising a casting, having an enlarged rim and a bearing in its closed end adapted to support a motor shaft, an outstanding flange, adapted to be secured to an engine leg, and stiffening webs connecting said enlarged rim and said flange.

10. In apparatus of the class described, in combination, an engine leg, a starting motor, having a shaft, a yoke and heads, one of said heads being cup-shaped, bearings for said shaft near the outer ends of said heads, said shaft being unsupported between said bearings, an automatic engine starting drive threaded on said shaft, and extending through said cup-shaped head, an outstanding flange integral with said head, between the outer end thereof and said yoke, and secured around an opening in said engine leg, whereby a part of said cup-shaped head and its inclosed drive is on one side, and said other head on the opposite side of said leg, said motor being unsupported at its ends, and means for preventing the entry of lubricating oil from said drive into said motor.

11. In apparatus of the class described, in combination, a motor, having a shaft, and an elongated head, an automatic engine starting drive threaded on said shaft, and extending within said elongated head, and centrifugal means connected with said shaft, and disposed between the armature of said motor and said starting drive, to throw oil from said drive outwardly.

35. 12. In apparatus of the class described, in combination, a dynamo electric machine, having a rotor, a plate rotatable with said rotor, an end head, and splash lubricated apparatus between said plate and said end head.

40. 13. In apparatus of the class described, in combination, a shaft having two bearings, one near each end, an armature of a dynamo electric machine, on one part of said shaft, a lubricated apparatus, on another part thereof, and an oil-throwing plate, surrounding said shaft between said armature and said apparatus and firmly secured to said shaft.

50. 14. In apparatus of the class described, in combination, a dynamo electric machine, having a shaft, and a head, said shaft having a shoulder, a plate surrounding said shaft and abutting said shoulder, and means for clamping said plate against said shoulder, said plate having an outwardly sloping flange on the side adjoining said head.

60. 15. In apparatus of the class described, in combination, a dynamo electric machine, having a head, and a plate rotatable with said machine, and located between the rotating parts of the machine and said head, to throw oil outwardly by centrifugal force, and means located near the periphery of

the armature of said motor for preventing oil from entering in that region.

16. In apparatus of the class described, in combination, a dynamo electric machine, having a casing, a head for said casing and a plate rotatable with said machine, and located between its armature and said head, to throw oil outwardly, and an annulus adjoining the outside of said casing to prevent oil from entering the armature at that region.

75. 17. In apparatus of the class described, in combination, a motor having a shaft, a casing and an elongated head for said casing, lubricated apparatus within said head, and driven by said shaft, and a plate 80 having a flange driven by said motor and located adjacent the armature thereof, to throw any oil reaching the plate away from the motor shaft, and an annulus clamped between the casing and the head, and overlapping said flange to prevent oil from entering the casing at that region.

85. 18. In apparatus of the class described, in combination, an engine leg, an engine drive housing having an enlarged rim at one end for embracing a starting motor yoke and a bearing near the other end for an operating shaft of an engine starting drive, an integral outstanding flange on said housing, remote from said bearing, and reinforcing webs connecting said flange and said enlarged rim.

90. 19. In apparatus of the class described, in combination, an engine leg, a flywheel associated therewith, a starting motor having a shaft, heads for said motor, one of said heads being elongated and having a bearing for said shaft near its outer end, a direct-acting outboard automatic starting drive within said elongated head, and co-operating with said flywheel at the side remote from said motor, and means for firmly supporting said motor, from said engine leg in a plane near the center of inertia of the motor, when the drive is in operative position.

105. 20. In apparatus of the class described, in combination, an engine, a starting motor, a flywheel for said engine having teeth on the half remote from said motor, said motor having a shaft and heads, one of said heads being elongated and having a bearing for said shaft near its outer end, a direct acting outboard screw-shift of the automatic type, having a driving pinion, adapted to co-operate with said flywheel teeth and flange means on a part of said motor for wholly supporting it around an opening in said engine leg.

115. 21. In apparatus of the class described in combination, an engine leg, a starting motor firmly secured with respect thereto, said motor having a head, a yoke, and a shaft

having a part projecting beyond said yoke at the end opposite said head, bearings for said shaft near its extreme ends, said shaft being unsupported between its bearings, and
5 being larger in diameter near its center than near its ends.

22. In apparatus of the class described, in combination, an engine leg, a starting motor, heads for said motor having bearings,

an engine starting drive between said heads, 10 and a flange on said motor near the center of inertia thereof, said leg having a deflected part to which said flange is secured.

In testimony whereof I have signed my name to this specification this 8th day of 15 February, 1917.

LIONEL M. WOLFFSOHN.
